(57) **CLAIM**

The ornamental design for a roof flashing, as shown and described.

DESCRIPTION

FIG. 1 is a top perspective view of a first embodiment of a roof flashing of the present invention;

FIG. 2 is a top view thereof;

FIG. 3 is a bottom view thereof;

FIG. 4 is a first side view thereof, wherein the opposing second side view is a mirror image thereof;

FIG. 5 is a front view thereof; and

FIG. 6 is a rear view thereof;

FIG. 7 is a top perspective view of a second embodiment of a roof flashing of the present invention;

FIG. 8 is a top view thereof;

FIG. 9 is a bottom view thereof;

FIG. 10 is a first side view thereof, wherein the opposing second side view is a mirror image thereof;

FIG. 11 is a front view thereof; and,

FIG. 12 is a rear view thereof.

The broken lines in the drawings depict portions of the roof flashing that form no part of the claimed design.

1 Claim, 8 Drawing Sheets
